WILLIAM W. ROBBINS, OF LORAIN, OHIO.

MINING MACHINERY.

Application filed December 4, 1920. Serial No. 428,290.

To all whom it may concern:

Be it known that I, WILLIAM W. ROBBINS, a citizen of the United States, residing at Lorain, in the county of Lorain and State 5 of Ohio, have invented certain new and useful Improvements in Mining Machinery; and I do hereby declare the following to be a full, clear, and exact description of the invention, such as will enable others skilled 10 in the art to which it appertains to make and use the same.

My invention relates to improvements in mining machinery, and more particularly it relates to mining machinery of the power 15 operated type.

Among the objects of my invention, are the following:—

To provide a machine of the above character with a power operated mining tool 20 which may be thrust directly into the wall of the vein, which machine may be raised and lowered as a whole, so that by a series of operations, a vertical channel may be made, the machine being raised one step before each thrust operation or after a series 25 of thrust operations;

To provide a machine of the above character with a wedge-shaped tool by means of which the mineral is dislodged;

To provide a machine of the above character which in addition to being raised and lowered, may have the tools set at any suitable angle, so that the mineral may be dislodged, thereby forming a trench way;

To provide a machine of the above character which may be set so that the tool may dislodge the mineral from any side of the trench and into the trench itself;

To provide a machine of the above character in which there is provided means directly connecting the piston with the tool head to prevent the tool from rotating;

To provide means in the cylinder head for preventing the tool from rotating;

To provide means for rotating the cylinder head whereby the tool may be set at any suitable angle;

To provide certain details of improvement tending to increase the efficiency and serviceability of a machine of the above character.

To accomplish the foregoing and other useful ends, my invention consists of means hereinafter more fully set forth and claimed.

Referring to the accompanying drawing, 55 Figure 1 is a view in elevation of the device. Figure 2 is an end view from left to right of Figure 1. Figure 3 is a front view of a tool holder. Figure 4 is a side view in elevation of the tool. Figure 5 is a front 60 view in elevation of the tool.

On a track 2, Figure 1, there is a frame 3 on rollers 4. Mounted on this frame, there is a motor 5 for driving a chain drive 6, which is geared with a pair of shafts 7 65 and 8, Figure 2. Said shafts are also supported on the frame 3, as will be seen. On the shaft 7, there is a beveled gear 9, which engages a corresponding beveled gear 10 on the lower end of the screw 11 which latter 70 is suitably journalled in the frame 3. On the opposite side of the frame, Figure 2, there is another screw 12 similar to the screw 11 and provided at its lower end with a beveled gear 13 corresponding to the 75 beveled gear 10, which latter engages a beveled gear on the shaft 8, corresponding to the beveled gear 9.

Supported between these screws 11 and 12, I provide a cylinder 14 in which a piston 80 15 reciprocates.

This may be controlled by water or any other suitable source of power, through the medium of pipes 16 and 17, which pipes are connected to suitable intake and exhaust 85 branches. On the left end of the cylinder 14 I provide a head 18 provided with shoes 19, one on each side, Figure 2, which bear on the surface of the head piece 20 of the frame 3, and which slide up and down on this 90 surface when the screws 11 and 12 are operated. This head piece may be removed and a new one substituted if it becomes necessary, due to the wear. The head 18 is provided on the outside with cross shaped members 21, over which there is provided a plate 22. When the machine is to be operated for mining purposes, an upright 23 is wedged between the ceiling and the floor or in any other suitable manner behind the cylinder 100 head against which the head may be braced to take the thrust of the machine. On either side of the cylinder 14, there is provided a nut. Through one of these nuts 24, the screw 11 passes and through the nut 25, the 105 screw 12 passes. It will be seen therefore, that whenever the screws 11 and 12 are rotated, the nuts 24 and 25 slide along the

threads of the screws, thereby lowering and raising the cylinder.

Connected to the piston 15 there are two piston rods 26 and 27, the piston rod 26 passing through gland 29 in the head 28 and the piston rod 27 passing through the gland 30 in the head 28. This arrangement of double piston rods is to prevent the tool from rotating. The said piston rods 26 and 10 27 terminate in the cross piece 31. To this cross piece 31, the tool 32, Figure 4, is attached through the medium of the screws 33. Fastened to the cylinder 14 just behind the head 28, there are a series of clamps 15 34 by means of which the cylinder head 28 is clamped and held in position. By loosening the clamps, the head 28 may be rotated, so that the tool 32 may be given any position desired.

20 It will be understood that I do not limit myself to this particular method of securing the cylinder head 28 and of rotating this cylinder head, as various other arrangements can be made which will serve the same purpose equally as well.

It will be seen therefore, that with this device after a preliminary opening is made in the vein, the tool 32 may be operated through the medium of the piston 15 so as to wedge out mineral along a given line. For example, if the opening should be at the lower left hand corner of the vein, the tool 32 may be arranged parallel to a horizontal plane and caused to bite into the vein just 30 above the preliminary opening, thus wedging down the mineral into the opening. The tool is then withdrawn, the cylinder 14 raised and the tool plunged again into the vein, which will cause still further mineral 35 to be wedged downward into the opening. This operation can be repeated and in this way a vertical trench will finally result rendering available all of the mineral that has been pried loose from this trench. When 40 the upward limit of the trench is reached, the tool 32 may then be rotated 90 degrees and the frame 3 moved forward along the track 2 a short distance. It will be seen when such a move is made it may also be necessary to move the up-right 23 and lock 45 the wheels 4.

The tool 32 can then be operated again through the medium of the piston 15 to bite into the vein a given distance beyond the 50 trench, whereby the mineral is wedged out from the vein into the upper limit of the trench, causing the mineral to tumble down along the trench toward the floor of the mine, from whence it may be removed by any suitable mechanism, as for example, by 55 means of a conveyor, or any other suitable manner.

The tool is then withdrawn, the cylinder 60 65 14 dropped a distance equal to the width of the tool 32 and another bite taken in the

vein and so on until the trench is widened all the way down. When the cylinder 14 reaches its lower limit, the frame 3 is again moved toward the vein and the same operation repeated in an upper direction, thereby 70 further widening the trench and so on, indefinitely. It will be seen that with the tool 32, the widening process can be conducted on either side of the vertical trench. Or, if the original trench instead of having been 75 made vertical, had been cut along a horizontal line the widening process would of course be upward, or under certain circumstances, downward, if necessary.

Of course the raising and lowering operation is controlled through the motor 5 and the operation of the tool 3 is controlled through the medium of the pipes 16 and 17.

It will be understood that although I have shown an upright 23 to receive the thrust of 80 the machine when the tool is to be pressed into the body of the mine, this upright may be substituted by an adjustable wall having sufficient area to permit the machine being raised and lowered and being slid along the 85 rails 2 some distance without having to reset the same. I further wish it understood that although I have shown the tool as a wedge with a straight cutting edge extending from the point 35 to the point 36, Figure 5, I do 90 not wish to so limit myself to the particular type of tool which can be used.

What I claim as my invention is:—

1. In a mining machine, in combination, a frame, wheels movably supporting the 100 frame, screw threaded members rotatably secured in a substantially vertical position in the said frame, means carried by the frame comprising a motor and gearing for rotating the said screw threaded members, a cylinder mounted for vertical movement in the said frame, and having screw threaded engagement with the said screw threaded members, a piston reciprocable in the cylinder, piston rods secured to the piston and 105 passing through one end of the cylinder and a cutting tool secured to the said piston rods.

2. In a mining machine, in combination, a frame substantially rectangular in horizontal cross section, and comprising upright 110 corner posts, screw threaded upright posts, an elongated cylinder movably mounted between the said corner posts, a piston reciprocable in the said cylinder and having two piston rods extending through one end of 115 the said cylinder, a cutting tool attached to the said piston rods, screw threaded lugs on the cylinder to engage the said screw threaded posts and means for rotating the said screw threaded posts and moving the said cylinder vertically.

3. In a mining machine, in combination a frame having spaced upright posts, a cylinder horizontally mounted to slidably engage the said posts, upright screw threaded posts 120

in the said frame, the screw threads of the said posts engaging correspondingly threaded parts of the cylinder, means for rotating the said screw threaded posts, means for resisting horizontal movement of the said cylinder with respect to the said frame, a cutting tool and means operatively con-

necting the said cutting tool and cylinder for reciprocatory motion of the said tool with respect to the cylinder. 10

In witness whereof, I have hereunto signed my name this 24 day of November, 1920.

WILLIAM W. ROBBINS.
